No. 668,354.

Patented Feb. 19, 1901.

S. OLDHAM.

PNEUMATIC IMPACT TOOL.

(Application filed Nov. 2, 1900.)

(No Model.)

UNITED STATES PATENT OFFICE.

SAMUEL OLDHAM, OF FRANKFORD, PENNSYLVANIA.

PNEUMATIC IMPACT-TOOL.

SPECIFICATION forming part of Letters Patent No. 668,354, dated February 19, 1901.

Application filed November 2, 1900. Serial No. 35,218. (No model.)

To all whom it may concern:

Be it known that I, SAMUEL OLDHAM, a citizen of the United States, residing at and whose post-office address is No. 4326 Tackawanna 5 street, Frankford, in the county of Philadelphia and State of Pennsylvania, have invented certain new and useful Improvements in Pneumatic Impact-Tools, of which the following is a specification.

10 My invention has relation to a pneumatic impact-tool of the type or class substantially illustrated in the Letters Patent No. 609,162, granted to me under date of August 16, 1898; and in such connection it relates to an im- 15 proved throttle for controlling the exhaust port or ports of the tool to thereby regulate the speed or stroke of the piston of the tool.

The principal object of my invention is to provide a simple and easily manipulated 20 throttle for controlling the outlet or exhaust from the tool, the throttle being so constructed and arranged that it may be quickly operated to secure the nicest adjustment or control of the exhaust and to thereby also secure a cor- 25 responding adjustment or control of the piston, which operates as a hammer upon the tool.

The nature and scope of my invention will be more fully understood from the following 30 description when taken in connection with the accompanying drawings, forming part hereof, in which—

Figure 1 is a front elevational view of the tool provided with a throttle embodying main 35 features of my invention. Fig. 2 is a transverse sectional view on the line 2 2 of Fig. 5, the throttle-disk being shown in elevation. Fig. 3 is a view similar to Fig. 2, but taken 40 on the line 3 3 of Fig. 5 and looking toward the left of said figure. Fig. 4 is a horizontal sectional view on the line 4 4 of Fig. 1, and Fig. 5 is a top or plan view of the tool.

Referring to the drawings, the cylinder or casing *a*, provided with the air, gas, or other 45 motive-fluid inlet *b*, the inlet-ports, and the piston or hammer *f* are all constructed and arranged and operate in substantially the manner shown and described in my prior patent, No. 609,162, hereinbefore referred to. It is, 50 however, to be understood that these parts, together with all the other necessary auxiliaries, may be arranged either as shown and

described in said patent or in any other suitable manner known in the art. From the interior of the cylinder *a*, above and below the piston *f*, are arranged the respective exhaust-ports *e* and *e'*, both of which terminate at one end of the tool, which, as illustrated, is preferably the upper end or head. This upper end or head is in the form of a cap *B*, screwed down upon the body of the tool. The cap *B* at the points where the exhaust-ports *e* and *e'* vertically traverse it is horizontally slotted or recessed, as at *g*, and in this recess *g* is inserted a ratchet-disk *k*. The disk *k* is pivoted at a point *k'*, between the ports *e* and *e'*, and is traversed by two openings *k*² and *k*³, which, as illustrated in Fig. 4, are not by preference diametrically opposite each other, but are radially disposed on one side the pivot *k'* of the disk *k*. These openings *k*² and *k*³ are adapted when the disk *k* is rotated on its pivot to completely register with the ports *e* and *e'* at one point only of the revolution of the disk *k*, and at other points in said revolution are adapted either to register in less and less with the ports *e* and *e'* or to slide beyond both of the said ports and permit the unperforated portion of the disk *k* to close the ports completely. The disk *k* is therefore a throttle 80 for the ports *e* and *e'*, and depending upon the turning of the throttle-disk *k* and the eccentric position of its openings *k*² and *k*³ one or the other of said ports *e* and *e'* may be completely or partly closed, or both may be completely or partly opened. It will be readily understood, therefore, that by turning the disk or valve *k* a gradual decrease or increase 85 of the area of the exhaust-ports *e* and *e'*, singly or combined, may be readily obtained and a consequent control of the stroke and speed 90 of the piston or hammer *f* may be secured. The disk or valve *k* has its periphery toothed or notched and is so pivoted in the cap *B* that a portion of the notched periphery of the disk 95 *k* projects beyond the periphery of the tool, as clearly illustrated in Figs. 2, 4, and 5. The valve *k* is therefore in position to be readily turned by the thumb or finger of the workman. Within the cap *B* is located a spring, pin, or pawl *m*, which fits against the notched periphery of the disk *k* to prevent accidental 100 turning of the said disk.

Having thus described the nature and ob-

ject of my invention, what I claim as new, and desire to secure by Letters Patent, is—

1. In a pneumatic impact-tool, a cylinder having a series of exhaust-ports, a cap adapted to be secured to said cylinder and traversed by said ports, a valve pivoted in said cap transversely to and in the path of the ports and a series of perforations traversing the valve and adapted to register gradually with the ports as the valve is turned in said cap, substantially as and for the purposes described.

2. In a pneumatic impact-tool, a cylinder provided with an exhaust port or ports extending longitudinally in one of its walls and terminating at one end of the cylinder, and a valve disposed at right angles to the longi-

tudinally-disposed port or ports and pivoted eccentrically to the axis of the cylinder so that a portion of the periphery of said valve projects beyond the periphery of the cylinder, said valve having one or more perforations traversing the valve and adapted to register with said ports as the valve is turned on its axis, substantially as and for the purposes described.

In testimony whereof I have hereunto set my signature in the presence of two subscribing witnesses.

SAMUEL OLDHAM.
